UNITED STATES PATENT OFFICE.

EUGENE H. LOWE, OF MODESTO, CALIFORNIA.

FUSE-PULLER.

1,247,555.

Specification of Letters Patent. Patented Nov. 20, 1917.

Application filed April 27, 1917. Serial No. 165,015.

To all whom it may concern:

Be it known that I, EUGENE HEBER LOWE, a citizen of the United States, and a resident of Modesto, in the county of Stanislaus and State of California, have invented new and useful Improvements in Fuse-Pullers, of which the following is a specification.

My invention is an improvement in fuse pullers, and has for its object to provide mechanism in connection with the ordinary fuse plug for permitting it to be engaged by the usual threaded insulator pin, to permit the withdrawal or replacement of the plug without requiring the same to be touched by the hands of the operator.

In the drawings:

Figure 1 is a side view of a plug, showing the manner of using the puller;

Fig. 2 is a bottom plan view of the plug; and

Fig. 3 is a sectional view showing the manner of connecting the pin with the plug.

In the present embodiment of the invention, the plug 1, which is of the usual construction, is shown in connection with the cut-out 2 of the transformer, mounted on the cross arm 3 of a pole 4. With the usual construction of fuse plug the operator,

when called out in what is termed transformer trouble must carry a cumbersome puller of complicated design for engaging the plug to pull the same. In order to dispense with this inconvenience, I thread the plug internally, as indicated at 5, in order that it may be engaged by an insulator pin 6 or like pin similarly threaded. With this arrangement, when the operator is called out he merely pockets an insulator pin, and he can handle the plug with the pin, obtaining a secure grip on the same by the threaded engagement between the pin and the plug. Such pins are always at hand about an electrical establishment, and the pin may be spliced to a pole, if necessary, to obtain additional length.

I claim:

A fuse plug provided in its lower end with an opening of a size and internally threaded to match the usual threaded end of an ordinary insulator pin to admit of such pin being used when it is required to remove and replace the plug.

EUGENE H. LOWE.
